UNITED STATES PATENT OFFICE

FLORENCE BARNARD, OF BROOKLINE, MASSACHUSETTS, ASSIGNOR TO MILTON BRADLEY COMPANY, OF SPRINGFIELD, MASSACHUSETTS, A CORPORATION OF MASSACHUSETTS

DESIGN FOR A GAME BOARD OR THE LIKE

Application filed April 14, 1931. Serial No. 39,482. Term of patent 14 years.

To all whom it may concern:

Be it known that I, FLORENCE BARNARD, a citizen of the United States, residing at Brookline, in the county of Suffolk and State of Massachusetts, have invented a new, original, and ornamental Design for Game Boards or the like, of which the following is a specification, reference being had to the accompanying drawing, forming a part thereof.

The figure is a top view of a game board or the like embodying my new design, all the elements of the design being flush with the top surface thereof and the board being of paper-like thickness.

I claim:

The ornamental design for a game board or the like as shown and described.

FLORENCE BARNARD.
